UNITED STATES PATENT OFFICE.

PAUL MACGAHAN, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRICAL PROTECTIVE DEVICE.

1,181,236.

Specification of Letters Patent.

Patented May 2, 1916.

Application filed January 30, 1914. Serial No. 815,389.

To all whom it may concern:

Be it known that I, PAUL MACGAHAN, a citizen of the United States, and a resident of Pittsburgh, in the county of Allegheny and State of Pennsylvania, have invented a new and useful Improvement in Electrical Protective Devices, of which the following is a specification.

My invention relates to electrical protective devices and particularly to relays, and it has for its object to provide a relay that shall be adapted to be interposed between a main circuit and the tripping coil of an automatic breaker for the circuit, in order 10 to operate the breaker a time interval after current that exceeds a predetermined value traverses the circuit, such time interval being inversely proportional to the amount by which the current exceeds a predetermined value.

It is the purpose of my present invention to provide a relay possessing exceedingly simple adjustments and having a performance curve that is flexible in extent and 25 of substantially a constant slope, thus securing an inverse time element in its operation.

The single figure of the accompanying drawings is a diagrammatic view of circuits and apparatus embodying my invention.

An electrical circuit 1 is provided with a circuit interrupter 2 and a relay 3 for controlling its tripping at predetermined overloads. The relay 3 comprises an electromagnet winding 4, a movable core member 5 therefor, and a bell crank lever 6 that is pivoted at a point 7 intermediate its ends. The lever 6 is operatively connected to a 35 rod 8 that extends upwardly from the movable core member 5 and is provided with a contact member 9.

An arm 10 of the bell crank lever 6 extends upwardly to engage a lever arm 11 that is pivoted at a point 12 located near one of its ends. The lever arm 11 has a relatively movable counter-balance weight 13 attached thereto for purposes hereinafter set forth. A contact member 14 and the 45 movable member 15 of a dash pot 16 are operatively connected to the lever arm 11, substantially as is shown in the drawing.

A dash pot 17 is connected to the lower end of the rod 8 for the purpose of steady- 50 ing the operation of the core 5, and a

spring 18, having one of its ends connected to the bell crank lever 6 and its other end to a stationary member, (not shown) is provided for effecting disengagement of the contact members 9 and 14 after the electromagnet coil 4 is deenergized. The contact members 9 and 14 constitute the separable terminals of a circuit 19 that comprises a battery 20 and an electromagnet coil 21. The electromagnet winding 21 has a movable core member 22 for tripping the circuit interrupter 2, as hereinafter explained.

If the counterbalance weight 13 is set in its proper position, and the dash pot 16 is adjusted for a given time element, and an 55 overload occurs in the circuit 1, my invention operates as follows: An increased current flowing through the winding 4 energizes it sufficiently to cause it to draw the movable core member 5 upwardly. This 60 movement of the member 5 causes the arm 10 of the bell crank lever to move downwardly correspondingly. The lever arm 11 is then free to move downwardly at a rate 65 that is controlled by the dash pot 16, so that 70 the time, after the appearance of the overload, when the contact members 9 and 14 75 are engaged may be adjusted to follow a definite law. The electromagnet coil 21 is 80 energized when the contact members 9 and 14 85 make contact with each other, and the movable core member 22 then trips the breaker 2 to open the circuit 1. When the 90 overload is removed from the circuit, less current flows through the electromagnet 95 coil 4 and the spring 18 draws the contact member 9 downwardly and moves the arm 10 of the bell crank lever 6 upwardly to engage the lever 11 and thus return the contact member 14 to its initial position. 100 When an increased current flows through the circuit 1 and the winding 4, the movable core 5 moves upwardly a distance that is 105 proportional to the magnitude of the overload and causes the arm 10 of the bell crank lever 6 to move downwardly twice the distance that the rod 8 moves upwardly because the distance from the pivotal point 7 to the rod 8 is one-half the distance from the point 7 to the elbow of the lever.

The lever arm 11 is free to move downwardly against the action of the dash pot 16 until it engages the arm 10 of the bell crank lever 6. The position of the arm 16 is controlled by the position of the movable 110

core member 5, but, since the position of the core member 5 is controlled by the value of the load traversing the circuit 1, it will be readily understood that the time that 5 elapses before the contact members 9 and 14 are engaged is inversely proportional to the load traversing the circuit 1. This will be understood since the distance between the contact members is inversely proportional 10 to the load traversing the circuit 1, and, since the distance to be traveled is less the higher the value of the load, less time will be required to engage the contact members.

While I have described my invention with 15 respect to a particular construction and method of connecting it to an electrical circuit, I desire that only such limitations shall be imposed as are set forth in the appended claims.

20 I claim as my invention:

1. An electromagnetic device comprising a pivoted lever arm having a contact member mounted thereon, means for retarding the movements of the said lever arm, an 25 electro-responsive device having a contact member mounted on its movable member, a bell-crank lever operatively connected to the movable member of the electro-responsive device and adapted to so control the position 30 of the pivoted lever arm that the distance between the contact members varies substantially inversely as the current traversing the electro-responsive device varies.

2. A relay comprising a pivoted lever arm 35 having a contact member mounted thereon, a dash pot operatively connected to the pivoted lever arm, an electromagnet winding, a movable core member therefor having a contact member mounted thereon, a pivoted 40 bell-crank lever operatively connected to the movable core member and adapted to so vary the position of the pivoted lever arm that the contact members are separated a 45 distance that is substantially inversely proportional to the current traversing the electromagnet winding.

3. A relay comprising a pivoted lever arm having a contact member mounted thereon, means for retarding the motion of the lever 50 arm in one direction, an electro-responsive device having a contact member mounted on

its movable member and means operatively connected to the movable member of the electro-responsive device for so controlling the position of the pivoted lever arm that 55 the distance between the contact members shall vary substantially inversely as the current that traverses the electro-responsive device varies.

4. A relay comprising a pivoted lever 60 arm, an electromagnet and a bell-crank lever operatively connected to the movable member of the electromagnet and adapted to so control the movement of the pivoted lever arm that the movable member of the 65 electromagnet will engage the said pivoted lever arm at the expiration of a period of time that varies substantially inversely as the current traversing the electromagnet varies. 70

5. A relay comprising a pivoted lever arm, a dash pot operatively connected to the lever arm for controlling its motion in one direction, an actuating device, a bell-crank lever operatively connected to the movable 75 member of the actuating device and adapted to control the position of the pivoted lever arm in accordance with the actuating force supplied to the actuating device and means for returning the pivoted arm to its 80 initial position when the actuating force is removed.

6. A relay comprising a pivoted lever arm, a dash pot for controlling its motion in one direction, an actuating electromagnet, 85 means operatively connected to the movable member of the electromagnet for controlling the position of the lever arm in accordance with the current traversing the winding of the electromagnet and means connected to 90 the movable member of the electromagnet for returning the pivoted lever arm to its initial position when no current traverses the winding of the electromagnet.

In testimony whereof, I have hereunto 95 subscribed my name this 24th day of Jan. 1914.

PAUL MACGAHAN..
